FIG. 4

FIG. 3

William B. Moses,
By Jesse A. Holton
Atty

UNITED STATES PATENT OFFICE.

WILLIAM B. MOSES, OF PORTLAND, MAINE.

ELECTRIC STARTING AND GENERATING APPARATUS.

Application filed March 30, 1917, Serial No. 158,547. Renewed October 4, 1922. Serial No. 592,442.

To all whom it may concern:

Be it known that I, WILLIAM B. MOSES, a citizen of the United States, and resident of Portland, in the county of Cumberland and 5 State of Maine, have invented certain new and useful Electric Starting and Generating Apparatus, of which the following is a specification.

This invention relates to electric starting, 10 generating and ignition apparatus for use in connection with the internal combustion engine of an automobile and with respect to certain more specific features thereof to Ford automobiles.

15 The invention has for one of its objects to provide a system of the character above-mentioned which shall be simple in construction and capable of installation in a quick and convenient manner.

20 Another object of the invention is to provide a so-called "two unit" starting and generating apparatus wherein the units are readily adjustable and wherein the weight of the system is evenly distributed.

25 Another object is to provide a housing for the elements of power transmission which comprises a bracket and parts related and assembled therewith in such a manner that the transmission elements are easily accessible.

30 Still another object of the invention lies in the provision of means for obtaining suitable motor torque multiplication.

35 Other objects will be in part obvious and in part pointed out hereinafter.

The invention accordingly consists in the various features of construction, combination of elements and arrangements of parts which will be exemplified by the construction hereinafter set forth and the scope of 40 the application of which will be indicated in the following claims.

In the accompanying drawings wherein is shown one of various possible embodiments 45 of the invention.

Fig. 1 is a plan view of a portion of the engine of an automobile with the invention applied thereto.

Fig. 2 is a front view of Fig. 1.

50 Fig. 3 is a right side elevation with certain parts in section to more clearly disclose the construction.

Fig. 4 is a left side elevation with certain

parts in section to more clearly disclose the 55 construction; and

Fig. 5 is an enlarged section taken on the line 5—5 of Fig. 2.

Referring now more particularly to the drawings wherein similar reference characters refer to similar parts throughout the 60 several views there is indicated generally at 1 an internal combustion engine having a timing shaft 2, and a crank shaft 3. The timing shaft may be driven in the usual way from a gear on the crank shaft to a gear 65 twice size on the timing shaft. These gears are suitably encased to run in oil in a housing 4 and this housing is provided originally with a cover plate which in the present instance is abandoned, as will more fully here- 70 inafters appear.

Referring now to Fig. 1 of the drawings a bracket 5 is shown positioned in a plane transversely of the crank shaft of the engine and at the forward end thereof. This 75 bracket is provided with several points of attachment certain of which are adjacent a flange 6 projecting forwardly on the engine casing, and certain of which are spaced around adjacent the timing gear housing 4. 80 The bracket attaching bolts are numbered 7 on the drawings.

The bracket 5 is provided on one side with three bolt holes 8, one of which is of a size 85 providing a sliding or rolling fit for the shank of an attaching bolt 9. The other two bolt holes are considerably larger than the shanks of the bolts which they are intended to receive, so that a motor unit 10 attached to the rear of the bracket by means 90 of the three bolts mentioned may be adjusted pivotally around the shank of the bolt 9 and secured in adjusted position by tightening up all three bolts. On the opposite side of the bracket similar attaching means are employed for securing a generator unit 11 to this side of the bracket. It will be noted that the pivotal movement of the generator unit is around the shank of a bolt 12 and that the bracket is provided with two larger bolt holes 13 and 14, similar to those through which the motor unit is attached.

Near the end of the timing gear shaft a sprocket 15 is mounted by threading the 100 same on to a threaded portion 16 of said 105

shaft. Originally this space was taken by a lock nut which served to hold the large timing gear in position, but in the present instance this lock nut is abandoned and the 5 sprocket 15 is substituted. A chain 17 serves to connect this sprocket with a smaller sprocket 18 fixed on the end of the armature shaft of the generator. The generator drive therefore is from the crank shaft 10 through the timing or half-time gears, through the timing shaft, sprocket 15, chain 17, small sprocket 18 to the generator armature. The bracket 5 is provided with a comparatively large circular opening 20 through 15 which the chain 17 may be inserted, positioned around its sprockets and secured in place. This opening is sealed by means of a plate 21 having a shoulder 22 fitting a flange 23 of the bracket and having an internally arranged packing ring fitting 20 around a hub 24 of the sprocket 15. This plate provides an oil tight encasement for the timing gear and sprocket 15 and is designed to prevent oil from passing through 25 to the make and break device 25 of the commutator 26. The original Ford roller arm, roller and commutator may be used, the roller arm being held in place by a lock nut 27. The plate 21 is recessed to receive 30 the commutator cap 28 and the bracket 5 is provided with means as indicated at 30 for attaching the original spring retaining arm 29 of the Ford machine to hold the commutator cap in position.

35 At the forward end of the crank shaft there is mounted a small pulley 31 the same being pinned or otherwise suitably secured to rotate with the crank shaft. This pulley is provided with a flange 32 on its forward side to which is bolted a gear 33. The motor unit is provided with an extended armature shaft carrying a fixed sprocket 34 which is connected by means of a chain 35 with a sprocket 36 forming part of a sleeve 45 37 which is journaled in the bracket 5 as at 38. (Fig. 3.) The sleeve 37 surrounds and is co-axial with a shaft 39, the two being connected by means of a coiled spring 40, one end of which is secured to the sleeve 37 as at 41 and the other end of which connects with a collar 42 which in turn is pinned or otherwise secured to the shaft 39. This shaft is intermediate the motor armature shaft and the crank shaft and a 50 portion of it is threaded as at 43 and has loosely mounted thereon an interiorly threaded unbalanced pinion 44. A range of travel of this pinion is permitted between stops 45 and 46 provided on the shaft 39 so that when the motor is operated the shaft 39 will be turned to cause a longitudinal movement of the pinion 44 into engagement with the gear 33. This will complete the 55 train of power transmitting devices between the motor and the engine and the en-

gine operating under its own power will cause automatic disengagement of the pinion with the gear 33.

The bracket 5 is formed with an oil receiving opening 50 through which the lubricating oil may be introduced over and around the sprocket 15 and the timing gears to the crank case of the engine.

In making an installation of the present apparatus the original crank shaft pulley of the Ford car may be removed and the combined pulley and gear 31 and 33, respectively, substituted. The original commutator, roller arm, timing gear lock nut, and timing gear housing cover may be removed and the bracket 5 positioned and secured by alining the various attaching points of the bracket with standard tapped holes in the timing gear housing and front flange of the Ford engine. The bolts 7 may be the original bolts used on the Ford car or some slightly longer. The bracket may be positioned with the generator and motor units attached or they may be mounted thereon later. The sprocket 15 is then screwed on to the threaded end of the timing shaft and as the driving tendency of the crank shaft is in the direction of the thread no further locking device is necessary, although one may be used if desired. The chain 17 is then arranged around the sprockets 15 and 18 and its ends secured, after which the sealing plate 21 may be applied. The original Ford roller-carrying arm is then returned to its initial position on a reduced end of the timing shaft, after which the locking parts are applied. It will be noted that in making the installation the Ford timing gear cover-plate is abandoned, the bracket 5 taking its place. The original commutator cap retainer or spring arm 29 is attached to the bracket at 30 and serves to hold the commutator cap as before which in turn holds the sealing plate 21 in position.

In operation the motor taking current from a storage battery (not shown), operates to drive the intermediate shaft 39 through the yielding connection 40 which causes an engagement of the pinion 44 with the gear 33 automatically. Through the pulley 31 the crank shaft is rotated from the gear 33 and when the engine commences to operate under its own fuel the pinion will be automatically disengaged in the usual manner. The generator is driven continuously from the crank shaft through the timing gears, sprocket 15, chain 17 and sprocket 18.

The present invention permits the retention of the original Ford make and break ignition device, while at the same time providing for the use of battery ignition by equipping the generator 11 with a timing device shown conventionally at 55.

As many changes might be made in the

above construction and as many apparently widely different embodiments of the invention might be made without departing from the scope thereof, it is intended that all matter set forth in the foregoing description or shown in the accompanying drawings shall be interpreted as illustrative and not in a limiting sense.

Having described the invention what I claim as new and desire to secure by Letters Patent is:

1. In apparatus of the character described, in combination, a cover plate for a timing gear housing of an engine characterized by an extension adapted to mount a generator, said extension having a rear attaching wall; a generator body, means between said body and said extension through which the body of the generator is attached to the extension, a generator armature shaft having a transmission device at one end, said extension and said means co-operating to house said device, and an ignition shaft driven from the armature shaft at the other end thereof.

2. In an apparatus of the character described, in combination, an internal combustion engine having a casing, a crank shaft, a timing shaft and a make-and-break device for ignition, a bracket supported forwardly of said engine provided with means for attachment to a forward flange of the engine casing and at points around the timing shaft, a generator attached to the bracket and extending rearwardly on one side of the engine, a motor attached to the bracket and extending rearwardly on the opposite side of the engine, a counter shaft journaled in the bracket, and power transmitting devices, including said counter shaft, for automatically connecting the motor with the crank shaft to start the engine and automatically disconnecting the motor from the crank shaft when the engine is running.

3. In an apparatus of the character described, in combination, an internal combustion engine having a casing, a crank shaft, a timing shaft and a make-and-break device for ignition, a bracket supported forwardly of said engine provided with means for attachment to a forward flange of the engine casing and at points around the timing shaft, a generator attached to the bracket and extending rearwardly on one side of the engine, a motor attached to the bracket and extending rearwardly on the opposite side of the engine, and means housed by said bracket connecting said timing shaft with said generator.

4. In an apparatus of the character described, in combination, an internal combustion engine having a casing, a crank shaft, a timing shaft and a make-and-break device for ignition, a bracket supported forwardly of said engine provided with means

for attachment to a forward flange of the engine casing and at points around the timing shaft, a generator attached to the bracket and extending rearwardly on one side of the engine, a motor attached to the bracket and extending rearwardly on the opposite side of the engine, and means housed by said bracket connecting said timing shaft with said generator, said bracket having a comparatively large opening on its forward side to permit access to said last means, and means for sealing said opening.

5. In generating and ignition apparatus for engines, a generator unit, mounting means for said generator comprising a member adapted to cover an open portion at the front of the engine and extend laterally beyond the engine, means for securing the generator unit by one end to the rear wall of said mounting means so that the generator unit and the mounting means may co-operate to house the transmission connections between the generator and engine, a member associated with said mounting means to provide an oil tight connection there-between and the timing shaft of the engine, and a battery ignition device at the end of the generator remote from the mounting means, said ignition device being included with an end cap of the generator unit.

6. In apparatus of the character described in combination, a two unit starting and generating system comprising means extending outwardly at opposite sides of the front of an engine adapted to support the units, said means having rear attaching faces, a generator unit mounted on said means with an end abutting one of said faces, a motor unit mounted on said means with an end abutting another of said faces, and power transmission devices for connecting said units with the crank shaft of the engine.

7. In apparatus of the character described, in combination, an engine having a crank shaft, a generator unit mounted on said engine at one side thereof having an armature shaft parallel with said crank shaft, a motor unit mounted on said engine at the other side thereof having an armature shaft parallel with said crank shaft and power transmission devices extending from both armature shafts to the forward end of the crank shaft, the means for mounting said units comprising laterally extending wings having rear attaching faces to which the ends of the units are secured.

8. In apparatus of the character described, in combination, a bracket for mounting starting and generating units, said bracket including cover means adapted to fit over an open front end of the engine and extend outwardly at each side thereof, a motor unit attachable by one end to an outward extension of said bracket at one

side of said engine, a generator unit attachable by one end to an outward extension of said bracket at the opposite side of said engine, and power transmission devices adapted to connect the said units with the forward end of the engine crank shaft.

9. In apparatus of the character described, in combination, a bracket adapted to be attached to the forward end of an engine to lie in a plane transversely of the engine crank shaft, said bracket having portions extending on either side of the engine for supporting a motor and a generator on respectively opposite sides of said engine, a 10 motor attached by one end to a rear wall of one extending portion, a generator attached by one end to a rear wall of the other extending portion and power transmission connection between the motor, generator 15 and crank shaft.

10. In apparatus of the character described, in combination, an engine, a motor, a generator, means at the front of said engine extending transversely thereof having 20 provision for attaching said motor and said generator by their ends, respectively, to hold them parallel to and on opposite sides of said engine, and transmission means connecting said motor and said generator with 25 said engine.

11. In apparatus of the character described, in combination, an engine, a motor, a generator, a member attached to the front of said engine extending transversely thereof 30 of adapted to adjustably support said motor and said generator rearwardly of itself and on opposite sides of said engine, and transmission means connecting said motor and said generator with said engine.

12. In apparatus of the character described, in combination, an engine comprising a crank shaft, a member attached forwardly of said engine and at right angles to said crank shaft, a motor attached rearwardly to said member on one side of said engine parallel to said crank shaft, and transmission means 40 partly supported by said member adapted to connect the motor and generator with the engine.

13. In apparatus of the character described, in combination, an engine comprising a crank shaft, a motor, a generator, a member extending transversely of said engine and attached forwardly thereto adapted to support said generator rearwardly on one side of said engine and to support said 50 motor rearwardly on the opposite side of said engine, a transmission device housed within said member for connecting said generator with said engine, and an automatically connectible and interruptible 60 transmission device supported by said mem-

ber for connecting said motor with said engine.

14. In apparatus of the character described, in combination, an engine, having a crank shaft, said shaft having mounted thereon a 70 member comprising a fan belt pulley and gear, a supporting member forwardly of said engine having provision for adjustably supporting a motor with a portion of its armature shaft extending through said supporting member, an intermediate shaft supported by said supporting member, means for transmitting rotative movement from said portion to said intermediate shaft, and means for transmitting rotative movement 80 from said intermediate shaft to the gear on said crank shaft.

15. In apparatus of the character described, in combination, an engine having a crank shaft, a fan belt pulley fixedly mounted on said shaft and comprising a gear, a motor having an extended armature shaft, a partially threaded shaft intermediate the armature and crank shafts, a sleeve surrounding said intermediate shaft, a yielding 90 connection between the sleeve and said intermediate shaft, a pinion movable longitudinally along the threaded portion of said intermediate shaft and adapted to engage with the gear of said fan belt pulley, means 95 for connecting said armature shaft with said sleeve, and means on said engine for supporting said motor and said intermediate shaft.

16. In apparatus of the character described, in combination, an engine comprising a crank shaft, a timing shaft, a timing gear thereon and a housing for said gear; a generating unit, a starting unit, a member forwardly of said engine at right angles to said crank shaft adapted to serve as a cover plate for said housing and having provision for supporting said generating and starting units, a transmission device housed in said member for driving said generating unit 105 from said timing shaft, and a transmission device connecting the starting unit with said crank shaft.

17. In apparatus of the character described, in combination, an engine comprising a crank shaft, a timing shaft, a timing gear and housing and a commutator at the end of said timing shaft; a generating unit, a starting unit, a transversely extending member forwardly of said engine between said timing gear and said commutator adapted to serve as a cover plate for said housing and having provision for adjustably supporting said units, a transmission device housed within said member for driving said generating unit from said timing shaft, and a transmission device automatically connectible and interruptible between said starting unit and said crank shaft.

18. In apparatus of the character de- 130

scribed, the combination with an internal combustion engine having a crank shaft, a timing gear shaft, and a make-and-break device on the end of the timing shaft for 5 ignition purposes; of a member adapted to be secured forwardly of said engine and transversely of said crank shaft, said member having a portion adapted to fit over the forward end of the timing shaft and receive 10 said make-and-break device, a generator having one end secured to the rear of said member, and a battery ignition device mounted at the other end of the generator.

19. In apparatus of the character described, in combination, an engine comprising 15 a timing gear, and a timing shaft having a threaded extending portion; a recessed sprocket having an elongated interiorly threaded hub adapted to engage with the 20 threaded portion of said timing shaft to secure said timing gear thereon, a generator with a transmission device adapted to be driven by said recessed sprocket, means at the front of said engine extending trans- 25 versely thereof adapted to support said generator and to house said transmission device, having a comparatively large opening to permit access to said device and comprising a cover for said opening, said cover com-

prising oil retaining means about the elongated hub of said recessed sprocket. 30

20. In apparatus of the character described, in combination, an engine comprising 35 a crank shaft and a timing shaft the latter being driven by the former at the forward end of the engine, a bracket member adapted to be secured to the forward end of the engine to serve as a cover plate for the engine casing opposite the driving connections between the crank shaft and timing 40 shaft; said bracket being adapted for penetration by an extending forward end of the timing shaft, a commutator on the timing shaft forward of said bracket member, an intervening element associated with said 45 bracket member and fitted around the timing shaft rearwardly of said commutator, and a generator unit supported at its forward end by means passing through an extending wing of said bracket into a part of 50 the generator unit; the bracket and unit being co-operatively associated also to provide a pocket for the transmission connections between the engine and generator. 55

Signed at Brookline, in the county of Norfolk and State of Massachusetts this tenth day of March A. D. 1917.

WILLIAM B. MOSES.
